UNITED STATES PATENT OFFICE

2,563,746

SHOWCASE HAVING INTERCONNECTED
CLOSURE AND TRAY

Paul M. Ressinger, Chicago, Ill.

Application July 28, 1945, Serial No. 607,601

8 Claims. (Cl. 312—117)

1

My invention relates to showcases having interconnected closure and tray. It has for one purpose to provide an improved display case.

Another purpose is to provide a display case which may be built up of a number of connected units.

Another purpose is to provide improved means for supporting the articles displayed.

Another purpose is to provide an improved display tray mechanism.

Another purpose is to provide improved shelf supporting means in connection with a display case.

Another purpose is to provide an improved combined display and storage assembly.

Other purposes will appear from time to time in the course of the specification and claims.

The invention is illustrated more or less diagrammatically in the accompanying drawings, wherein:

Figure 1 is a front perspective;

Figure 2 is a rear perspective;

Figure 3 is a section on the line 3—3 of Figure 2;

Figure 4 is a section on an enlarged scale on the line 4—4 of Figure 3;

Figure 5 is a detailed section;

Figure 6 is a section on the line 6—6 of Figure 3;

Figure 7 is a section on an enlarged scale on the line 7—7 of Figure 6; and

Figure 8 is a section taken at line 8—8 of Figure 5.

Like parts are indicated by like symbols throughout the specification and drawings.

Referring to the drawings 1 indicates a base element which may rest upon any suitable surface such as the floor of the room in which the unit is positioned. Resting upon the base and preferably removably secured thereto, are a central show case assembly generally indicated as A, and two side assemblies generally indicated as B and C. Spanning the side assemblies and removably secured thereto, is a top or roof member generally indicated as D. It will be understood that the assemblies may be removably bolted or secured in any suitable fashion to the base 1 and the members B and C may be secured to the assembly A for example by the bolts or screws indicated at 2, which may pass through any suitable intermediate spacing members or frames, indicated for example at 3 in Figure 3. It will be observed that the top of the assembly A is substantially lower than the tops of the assemblies B and C and that a substantial space is

2

thus provided between the top of the assembly A and the bottom of the cross member D. Referring to the assembly A, it is shown as including a lower storage portion and an upper show case portion. The storage portion may be bounded by side walls 4 and 5, a bottom wall 6, and a top wall 7. Intermediate horizontal partitions 8 and 9 may be employed to define storage spaces which are rearwardly open. I illustrate for example a series of drawers 10 between the partitions 7 and 8 and a series of larger drawers 11 between the partitions 8 and 9. The space below the partition 9 may serve as a storage space through which access may be had through sliding doors 12.

The show case portion of the assembly A has transparent front, side and top walls as indicated at 14, 15 and 16. Access is had through the rear, as by the door or doors 17 pivoted at their lower edges as at 18 and provided with any suitable locking or securing means 19 for holding them in the locked or full line position of Figure 6. It will be noted as in Figure 6 that the top partition 7 is of substantial thickness. It is provided with a sunk guiding element in the form of a channel 20 having a cover plate 21 provided with a slot 22 substantially less in width than the channel 20 but having an opening 23, intermediate its ends, of substantially the same width as the channel. 24 generally indicates a goods support which is pivoted to the rear door 17. I illustrate for example a lug or lugs 25. At its forward end is provided a downwardly extending lug or arm 26 carrying a cross member 27 which carries a pivot pin 28 on the end of which are mounted rollers 29. It will be observed that, except that when the rollers 29 and the cross members 27 are aligned with the opening 23, the support 24 cannot be upwardly withdrawn from the partition 7. The rollers 29 constitute supporting means for the forward downward end of the shelf 24. As a means for securing the shelf 24 to the door 17 I employ brackets 30 which have associated with them springs 31 on the ends of which are inwardly extending pins 32 adapted to engage any suitable apertures in the lug or lugs 25. Each of the springs 30 has an end portion 33 adapted for manual operation whereby, by outward flexure of the springs 31 the pins 32 may be withdrawn and the shelf structure 24 removed from the door 17. The support may carry any suitable cross members 35 upon which the goods to be displayed, such as trays 36 may be removably positioned.

It will be noted that in the full line position

of Figure 6 the weight of the tray, pivoting about the wheels 29, and directed against the inner end of the brackets 30, is effective to bias the door 17 toward closed position even though the lock 19 is released. However, when the door is moved to the open or dotted line position of Figure 6 the member 24 and with the display trays 36 is rearwardly withdrawn, and serves as a stop for limiting the downward opening movement of the door 17. Any suitable abutment of yielding material may be employed at the rear edge of the partition 1. When the user wishes to remove the member 24 he can do so by aligning the rollers 29 and the cross piece 27 with the opening 23 and lifting upwardly on the member 24.

An additional display or storage area is illustrated in the front section of the assembly A below the show case portion. I illustrate for example front wall portions 40, 41, each with any suitable lock 42, 43. A single transparent panel 44 may be employed which can be slid in either direction, to give access to all parts of any suitable shelf structure or structures 45. The panel may be locked in its central or closed position by actuation of the two locks 42, 43. The release of either lock will permit the panel to be moved in one direction, and the release of both locks will permit the panel to be moved in either direction. The display area above described may be illuminated by any suitable light source diagrammatically indicated as at 46 in Figure 6.

The side display members or assemblies B and C each include a lower storage portion 50 resting directly upon the base 1. The storage portions may have any suitable rear access doors 51. I find it convenient to have the storage portions 50 the same height as the storage portion of the central assembly A. Above each storage portion is a display portion which includes roofs or covers 52 upon which the transverse assembly D is removably mounted. Vertical side frame members or mullions 53 are employed, which serve, with the rear frame members 54, to support shelves 55 mounted by any suitable adjusting securing pins or members 56. The sides of the display members, as at 57, may be constituted by members of plate glass or other suitable transparent material. I find it desirable to employ a front member 58 having curved corners 59, the front member being of Lucite or other suitable plastic transparent material. The inner edges of the Lucite panels are received in recesses in the mullions 53 which, therefore, will perform the double function of serving as shelf supports and as means for joining the opposed edges of the panels of transparent material. The mullions 53 may be provided with a plurality of apertures 53a adapted to receive the shelf supporting pins 56 at a variety of different elevations. The display portions of the assemblies B and C may have any suitable rear access doors 65.

The top cross assembly D may serve as an illuminating means for the goods displayed. It includes end members 60 which carry an upwardly enlarged central member 61. This central member serves as an enclosure for any suitable light source diagrammatically indicated as at 62. The member 61 may have a front pane 63 of transparent or translucent or partly transparent material. It may carry for example any suitable descriptive lettering or trademark. The lower surface of the member 61 may also be transparent or translucent, in order that the light source 62 may be employed to direct light upon the goods displayed within the show case or dis-

play portions of the assemblies A, B and C, or the bottom may be left open. In any event the light source 62 is suitably housed in the housing 61, and not directly visible to the eye of the observer and provides adequate and easily directed or concentrated light for the displayed goods.

It will be realized that, whereas, I have described and illustrated a practical and operative device, nevertheless many changes may be made 10 in the size, shape, number and disposition of parts without departing from the spirit of my invention. I therefore wish my description and drawings to be taken as in a broad sense illustrative or diagrammatic, rather than as limiting 15 me to my precise showing.

I claim:

1. In a display device, a display case having transparent walls and a rear closure, said rear closure being pivoted for rotation about a horizontal axis adjacent its lower edge, said case having a bottom wall provided with a guiding channel generally perpendicular to the rear closure when the closure is in closing position, a display support mounted within said display case 20 and having a forward supporting guide extending into and slidably along said channel, said channel having a slotted cover, the slot of said cover being of less width than the width of the supporting guide, said slot having an enlarged portion 25 of a width greater than that of said guide and a hinge connection between said rear closure and the rear portion of said support.

2. In a display device, a display case having transparent walls and a rear closure, said rear closure being pivoted for rotation about a horizontal axis adjacent its lower edge, said case having a bottom wall provided with a guiding channel generally perpendicular to the rear closure when the closure is in closing position, a display support mounted within said display case 30 and having a forward supporting guide extending into and slidably along said channel, said channel having a slotted cover, the slot of said cover being of less width than the width of the supporting guide, said slot having an enlarged portion of greater width than said guide, and a removable hinge connection between said rear closure and the rear portion of said support.

3. In a display device, a display case having transparent walls and a rear closure, said rear closure being pivoted for rotation about a horizontal axis adjacent its lower edge, said case having a bottom wall provided with a guiding channel generally perpendicular to the rear closure 35 when the closure is in closing position, a display support mounted within said display case and having a forward supporting guide extending into and slidably along said channel, said channel having a slotted cover, the slot of said cover being of less width than the width of the supporting guide, and having an enlarged portion of greater width than said guide, and a removable hinge connection between said rear closure and the rear portion of said support, including a bracket extending 40 forwardly from said rear closure at a level substantially above its horizontal axis.

4. In a display device, a display case having transparent walls and a rear closure, said rear closure being pivoted for rotation about a horizontal axis adjacent its lower edge, said case having a bottom wall provided with a guiding channel generally perpendicular to the rear closure 45 when the closure is in closing position, a display support mounted within said display case and having a forward supporting guide extending into

and slidable along said channel, said channel having a slotted cover, the slot of said cover being of less width than the width of the supporting guide, and having an enlarged portion of greater width than said guide, and a removable hinge connection between said rear closure and the rear portion of said support, including a bracket extending forwardly from said rear closure at a level substantially above its horizontal axis, a hinge element on said support and an interpenetrating pin connection between said bracket and said hinge element.

5. In a display device, a display case having transparent walls and a rear closure, said rear closure being pivoted for rotation about a horizontal axis adjacent its lower edge, said case having a bottom wall provided with a guiding channel generally perpendicular to the rear closure when the closure is in closing position, a display support mounted within said display case and having a forward supporting guide extending into and slidable along said channel, said channel having a slotted cover, the slot of said cover being of less width than the width of the supporting guide, and having an enlarged portion of greater width than said guide, and a removable hinge connection between said rear closure and the rear portion of said support, including a bracket extending forwardly from said rear closure at a level substantially above its horizontal axis, a hinge element on said support and an interpenetrating pin connection between said bracket and said hinge element, said connection including a spring mounted on said bracket and a pin on said spring, said spring being adapted for manual flexure to withdraw the pin.

6. In a display device, a showcase having transparent front and top walls, side walls and a bottom member, a rear closure for said showcase mounted along its lower edge for rotation about a horizontal axis generally parallel with the front of the showcase, a display tray in said showcase, forwardly supported on the bottom of the showcase and removably hinged, at its rear, to said rear closure and a guiding connection interposed between the forward portion of said tray and the bottom member of said showcase, adapted, by means of a guiding channel containing an opening spaced a predetermined distance along said guiding channel, to prevent upward displacement of said tray when said rear closure is in generally upright, closed position, and adapted, by reason of the aforesaid guiding channel, to permit upward removal of the forward portion of said tray when said tray has been rearwardly withdrawn a predetermined distance, during the rotation of said closure toward open position.

7. In a display device, a showcase having transparent front and top walls, side walls and a bottom member, a rear closure for said showcase

mounted along its lower edge for rotation about a horizontal axis generally parallel with the front of the showcase, a display tray in said showcase, forwardly supported on the bottom of the showcase and removably hinged, at its rear, to said rear closure and a guiding connection interposed between the forward portion of said tray and the bottom member of said showcase, adapted, by means of a guiding channel containing an opening spaced a predetermined distance along said guiding channel, to prevent upward displacement of said tray when said rear closure is in generally upright, closed position, and adapted, by means of the aforesaid guiding channel, to permit upward removal of the forward portion of said tray when said tray has been rearwardly withdrawn a predetermined distance, during the rotation of said closure toward open position, said guiding connection including means for preventing upward withdrawal of the forward portion of said tray when the rear closure is in fully open position.

8. In a display device, a showcase having transparent front and top walls, side walls and a bottom member, a rear closure for said showcase, mounted along its lower edge for rotation about a horizontal axis generally parallel with the front of the showcase, a display tray in said showcase, forwardly supported on the bottom of the showcase and removably hinged, at its rear, to said rear closure, intermediate the top and bottom of the closure, and a guiding connection interposed between the forward portion of said tray and the bottom member of said showcase, said guiding connection including a laterally extended supporting part positioned below the forward end of the tray, the upper surface of the showcase having a slotted receiving element positioned below the tray and adapted to receive said supporting part, the slot of said receiving element being of less width than said supporting part, whereby said guiding connection is adapted to prevent unintended upward displacement of the forward end of the tray.

PAUL M. RESSINGER.
